Primary Examiner — Susan E Krakower*Assistant Examiner* — L. A. Grabenstetter(74) *Attorney, Agent, or Firm* — Davis Wright Tremaine LLP(57) **CLAIM**

The ornamental design for a handbag, as shown and described.

DESCRIPTION

FIG. 1 is a top perspective view of a handbag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines, and unshaded surfaces bounded by broken lines, depict parts of the handbag's appearance that form no part of the claimed design.

1 Claim, 6 Drawing Sheets(56)
